[57] CLAIM

The ornamental design for a combined revolving spice rack and spice grinder containers, as shown and described.

DESCRIPTION

FIG. 1 is a view in perspective of a combined revolving spice rack and spice grinder containers showing my new design;

FIG. 2 is a side elevational view thereof;
FIG. 3 is a top plan view thereof;

FIG. 4 is a bottom plan view thereof;

FIG. 5 is a top, front, right side perspective view of an alternative embodiment of FIG. 1, the rear and left side views being mirror images of those shown and the bottom view being similar to FIG. 4; and,

FIG. 6 is a perspective view similar to FIG. 1 with the spice grinder containers removed for clarity of illustration.
